TOY STAGE FOR PUPPETS

Hazelle H. Rollins, Kansas City, Mo.

Application July 30, 1953, Serial No. 26,197

Term of patent 14 years

(Cl. D34—15)

To all whom it may concern:

Be it known that I, Hazelle H. Rollins, a citizen of the United States, residing at 801 West 63rd Street, Kansas City, in the county of Jackson, and State of Missouri, have invented a new, original, and ornamental Design for a Toy Stage for Puppets, of which the following is a specification, reference being had to the accompanying drawing, forming a part thereof.

Fig. 1 is a top plan view of a toy stage for puppets, showing my new design.

Fig. 2 is a front elevation view thereof;

Fig. 3 is an end elevation view thereof; and

Fig. 4 is a rear elevation view of the toy stage for puppets.

I claim:

The ornamental design for a toy stage for puppets, as shown.

HAZELLE H. ROLLINS.
